UNITED STATES PATENT OFFICE

WALTER M. HANNEMAN, OF EVANSVILLE, INDIANA, ASSIGNOR TO UNION SPECIAL MACHINE COMPANY, OF CHICAGO, ILLINOIS, A CORPORATION OF ILLINOIS

FEED-OFF-THE-ARM SEWING MACHINE

Application filed September 14, 1928. Serial No. 305,945.

The invention relates to new and useful improvements in sewing machines wherein the material being stitched is fed off the end of an arm, and more particularly to a means for supporting and actuating a trimming mechanism and also a thread covering mechanism.

An object of the invention is to provide a sewing machine of the above type wherein the support for the trimming blade is operated by a direct connection to a rock shaft at the rear of the machine and parallel with the overhanging arm, and wherein the thread hook for forming a loop in the cross thread is likewise directly operated by a link connection with said rock shaft.

A further object of the invention is to provide a sewing machine of the above type wherein the arm carrying the movable trimming blade is mounted on a collar which, in turn, is mounted on a sleeve surrounding the presser bar and extending therewith through the lower supporting lug on the needle head, said sleeve being connected to said bar so as to move endwise therewith and so as to oscillate freely thereon.

A further object of the invention is to provide a sewing machine of the above type wherein the thread hook is mounted on an arm carried by a yoke which, in turn, is mounted for free oscillation on the sleeve carrying the trimming blade and which is held from endwise movement by a supporting lug which lies between the arms of the yoke.

These and other objects will in part be obvious and will in part be hereinafter more fully disclosed.

In the drawings, which show by way of illustration one embodiment of the invention:

Fig. 1 is a front view of a portion of a machine embodying the improvements.

Fig. 2 is a view of a portion of the work supporting arm in side elevation and of the overhanging arm in end elevation.

Fig. 3 is a view from the rear of the machine.

Fig. 4 is a view showing the arrangement of the sleeve carrying the trimming blade on

the presser bar and the yoke carrying the thread hook on the sleeve carrying the trimming blade and the position of said parts relative to the supporting lug in which the presser bar is mounted.

Fig. 5 is a top plan view of the parts at the end of the overhanging arm, said view being partly in section so as to show the connections between the thread hook supporting yoke and the trimmer blade supporting sleeve and the rock shaft.

Fig. 6 is a section showing the operating mechanism for the thread hook in plan.

The sewing machine includes a supporting base on which is mounted a work supporting arm. Also mounted on this supporting base is an overhanging arm having a needle head disposed above the free end of the work supporting arm. Within the work supporting arm is a looper mechanism and a feeding mechanism arranged so as to feed the material off the end of the arm as it is stitched. Mounted for reciprocation in the needle head is a needle bar. A presser bar is also mounted in the needle head and carries a presser foot for holding the material on the work support. Surrounding said presser bar and extending through the lower supporting lug therefor is a sleeve which is free to oscillate in the lug and on the bar but which moves endwise with the presser bar. The movable trimming blade is carried by an arm clamped to the lower end of this sleeve. The sleeve adjacent its upper end is provided with a yoke which spans a collar secured to the presser bar and having connection with a guide bar for preventing the presser bar from turning. This yoke carries a ball stud to which a link is connected.

At the back of the machine there is a rock shaft with a depending arm and this link is connected to the arm so that the rock shaft imparts oscillations to the sleeve carrying the trimming blade. Also mounted on this sleeve is a yoke which spans the supporting lug for the sleeve and this yoke has an arm carrying a thread hook. The arm is connected by a link to a depending arm on the rock shaft and thus it is that the rock shaft oscillates the thread hook. This rock shaft

is oscillated by an eccentric strap cooperating with an eccentric on the main shaft.

Referring more in detail to the drawings, the sewing machine includes a base or standard 1 on which is mounted a work supporting arm 2. The free end of this work supporting arm carries a feed dog 3 and a looper. Also mounted on the base or standard 1 is an overhanging arm 5. At the outer end of this overhanging arm is a needle head 6 in which a needle bar 7 is mounted for reciprocation.

Attached to the overhanging arm is a needle lever 8 which is connected to the needle bar for reciprocating the same. The material is held on the work support by a presser foot 9. This presser foot 9 is carried by a presser bar 10 mounted in lugs 11 and 12 formed as a part of the needle head. Also mounted in the lower lug 12 is a guide bar 13. The presser bar is provided with a collar 14 which is secured thereto and this collar has an arm 15 straddling the guide bar, which prevents the presser bar from oscillating in its supporting bearing.

Surrounding the presser bar 10 is a sleeve 16. This sleeve is provided with an integral arm 17 at its upper end and this arm 17 carries a projecting portion provided with a collar 18. The collar 18 and the end of the sleeve are disposed on opposite sides of the fixed collar 14 on the presser bar. Thus it is that the sleeve is limited in its endwise movement on the presser bar. A spring 19 bears against the collar 18 and normally forces the sleeve in a downward direction. At the lower end of the sleeve 16 is a bracket arm 20 which carries the movable trimming blade 21. Said bracket arm is carried by a collar which surrounds the sleeve; said collar is split and the ends thereof are joined by a screw. This provides an adjustable mounting for the arm. This blade 21 overlies a stationary blade 22 and the spring bearing on the collar yieldingly holds the movable blade in shearing contact with the stationary blade. At the back of the machine there is a rock shaft 23. This rock shaft is oscillated by an eccentric strap 24 which cooperates with an eccentric on the main shaft. At the outer end of the rock shaft there is a sleeve 25 which is fixed to the rock shaft. This sleeve is provided with an arm 26 extending in the general direction of the rock shaft, but offset from the center thereof. On the outer end of the arm 26 is a ball stud 27. A link 29 engages this ball stud 27 and also engages a ball stud 30 on the arm 17 which is attached to the sleeve carrying the trimming blade. As the rock shaft oscillates this link will impart oscillations to the sleeve which will, in turn, oscillate the trimming blade.

Also mounted on this sleeve is a yoke member 31. The yoke member 31 straddles the lower bearing lug 12 in which the sleeve is mounted for oscillation. This yoke member

31 is provided with a laterally projecting arm 32. Depending from the arm 32 is a sleeve member 33 in which the thread hook 34 is mounted. Also carried by the arm 32 is an upwardly extending member 35 on which a ball stud 36 is mounted. A link 37 engages this ball stud and also engages a ball stud 38 at the lower end of a depending arm 39 fixed to the sleeve 25 on the rock shaft 23. When this rock shaft oscillates it will impart oscillations to the yoke, which, in turn, will oscillate the thread hook. The yoke supporting the thread hook is free to oscillate about the center of the presser bar as an axis. It is, however, held from movement up and down with the presser bar by reason of the fact that it straddles the lower lug 12 on the needle head. Associated with the thread hook is a thread guide 40 carried by a fixed arm 41 attached to the needle head.

From the above it will be apparent that the sewing machine is provided with devices for oscillating the movable trimmer blade and the thread hook which are of comparatively few parts, as the thread hook supporting means is connected directly by a link to an arm on a rock shaft, while the sleeve carrying the arm supporting the trimming blade is likewise directly connected by a link to an arm on the same rock shaft. Not only has the actuating mechanism been greatly simplified, but the supporting bearings for both the sleeve which carries the arm on which the trimming blade is mounted and the yoke which carries the arm on which the thread hook is mounted are so constructed as to provide a very rigid support for these members so that they may be oscillated at very high speed and yet the parts moved will be held to their proper paths of movement.

It will be obvious that minor changes in the details of construction and the arrangement of the parts may be made without departing from the spirit of the invention as set forth in the appended claims.

Having fully described my invention, what I claim as new and desire to secure by Letters Patent, is:—

1. In a sewing machine the combination of a work support, a needle head directly above the free end of said work support, a presser foot, a presser bar mounted in spaced lugs in said needle head, a sleeve surrounding said presser bar and extending through the lower lug, an arm adjustably carried by the sleeve, a movable trimming blade carried by the arm, said sleeve being free to oscillate on said presser bar and limited in its endwise movement thereon, a rock shaft, and a link connecting said rock shaft to said sleeve for oscillating the sleeve.

2. In a sewing machine the combination of a work support, a needle head directly above the free end of said work support, a presser foot, a presser bar mounted in spaced lugs

in said needle head, a sleeve surrounding said presser bar and extending through the lower lug, an arm carried by the sleeve, a movable trimming blade carried by the arm,
5 said sleeve being free to oscillate on said presser bar and limited in its endwise movement thereon, a rock shaft, a link connecting said rock shaft to said sleeve for oscillating the sleeve, a collar surrounding the presser
10 bar connected to said sleeve and spaced from the end thereof, a spring surrounding the presser bar and bearing against said collar, a collar fixed to the presser bar beneath the collar which is attached to the sleeve, and
15 means cooperating with the collar fixed to the presser bar for preventing the presser bar from oscillating.

3. In a sewing machine the combination of a work support, a needle head directly above
20 the free end of said work support, a presser bar mounted in spaced lugs in said needle head, a sleeve surrounding said presser bar and extending through said lower lug and free to oscillate therein, means for limiting
25 the endwise movement on the presser bar, a trimming blade carried by said sleeve, a yoke surrounding said sleeve and straddling the lower supporting bearing for said sleeve, a thread hook carried by said yoke, a horizontal
30 rock shaft, an arm carried by the rock shaft, a link connecting said arm to said sleeve for oscillating the sleeve, a second arm depending from said rock shaft, and a link connecting said second arm with said
35 yoke for oscillating the thread hook.

4. In a sewing machine the combination of a standard, an overhanging arm, a work support, a needle head at the outer end of the overhanging arm, a rock shaft extending
40 lengthwise of the overhanging arm, a presser bar mounted in spaced bearings in the needle head, a presser foot carried thereby, a sleeve surrounding said presser bar and extending through the lower lug and free to
45 oscillate therein, means for limiting the endwise movement of the sleeve on the presser bar, an arm carried by the sleeve, a ball stud mounted on said arm, an arm projecting from said rock shaft, a ball stud thereon, a link
50 connecting said ball studs, a yoke mounted on said sleeve and straddling the lower bearing, said yoke being free to oscillate on the sleeve and held by the bearing from endwise movement, a thread hook carried by said
55 sleeve, a ball stud mounted on said sleeve, a depending arm carried by the rock shaft, a ball stud thereon, and a link connecting the last-named ball studs whereby the rock shaft oscillates the thread hook.

60 In testimony whereof, I affix my signature.
WALTER M. HANNEMAN.
